UNITED STATES PATENT OFFICE

ANTONIN BOULADE, OF LYON, FRANCE, ASSIGNOR TO SOCIETE DU CARBURATEUR
ZENITH, OF LYON, FRANCE

CARBURETOR

Application filed March 25, 1925, Serial No. 18,196, and in France April 2, 1924.

The present invention relates broadly to carburetors, and more particularly to carburetors of the so-called multiple Venturi type and to means for improving the efficiency 5 and operation thereof.

At the present time it is proposed to construct carburetors having a main outer venturi and one or more inner or secondary venturis for the purpose of imparting a higher 10 velocity to at least a portion of the air supplied to the engine served by the carburetor. By reason of the high velocity of this portion of the air, and by reason of the location of such secondary venturi or venturis, they are 15 subjected to a strong cooling action due to such velocity and due to the vaporization of the fuel. Such secondary venturis are in very poor thermal contact with the main body of the carburetor and, therefore, do not receive any appreciable heat from the carburetor body such as the carburetor body itself 20 receives either by reason of its proximity to the motor or by its own system of heating.

In actual operation, as the temperature of 25 these inner or secondary venturis is decreased or lowered, they become coated or covered with ice due to the condensation of the humidity in the air. This ice not only impairs vaporization of the fuel and results in the undesirable condensation of a large portion 30 thereof, but also clogs to a greater or lesser extent the orifices through which the fuel passes into the air stream, and also decreases the effective area of the air passages so that the 35 mixture may be disproportionately enriched.

The present invention has for its objects 40 improvements in carburetors of the so-called multiple Venturi type for the purpose of overcoming and obviating these difficulties and improving the efficiency and operation thereof.

In the accompanying drawings there are 45 shown, for purposes of illustration only, certain embodiments of the present invention, it being understood that the drawings do not define the limits of my invention and that changes in the construction and operation 50 therein disclosed may be made without de-

parting either from the spirit of the invention or the scope of my broader claims.

In the drawings:—

Figure 1 is a vertical sectional view through a multiple Venturi carburetor in accordance 55 with one embodiment of my invention;

Figure 2 is a view similar to Figure 1 illustrating a carburetor having a double or compound secondary venturi;

Figure 3 is a view similar to Figure 1 illustrating a slightly different embodiment of my invention;

Figure 4 is a view similar to Figure 2 illustrating a double or compound secondary venturi in a carburetor of the character shown in 65 Figure 3;

Figure 5 is a view similar to Figure 1 illustrating a carburetor having electrical heating means for the secondary venturi;

Figure 6 is a view similar to Figure 2 showing 70 a double or compound secondary venturi having electrical heating means, and

Figure 7 is a view partly in section and partly in elevation illustrating another embodiment of the invention. 75

The present invention is adapted particularly to multiple Venturi carburetors and to means for raising the temperature of at least one of the inner venturis irrespective of the temperature of the outer venturi or venturis. 80

In carrying out the present invention there may be provided a carburetor comprising a body 2 having an expanding air inlet 3 and provided with the usual main outer venturi

4. Disposed in coaxial relationship to the outer venturi is an inner or secondary venturi 5 preferably having its outlet end disposed in or adjacent to the region of maximum depression in the outer venturi, this zone ordinarily being slightly above the point of maximum 90 restriction of the outer venturi. In constructions of this character, the inner venturi is substantially isolated from the main carburetor body whereby it is not materially affected thermally by the temperature of the main carburetor body. By reason of this location and by reason of the operation of the carburetor as set forth it is desirable to provide means

for raising the temperature of the inner venturi. In the embodiment of the invention il- 100

lustrated in Figure 1 this is accomplished by providing a jacket 6 surrounding the inner venturi and adapted to receive a supply of a heating medium, such as heated air or exhaust gases, through a passage 7. Actual experiments have shown that a small percentage of such a heating medium may be introduced into the mixture with no harmful results, and for this purpose the jacket 6 is preferably formed with an annular discharge opening 8 insuring a continuous circulation of heated gases through the jacket. The inner venturi may be supplied with fuel, or a mixture of fuel and air, in known manner through a passage 9 feeding a chamber 10 having discharge orifices 11 through the wall of the venturi. With a construction of this character it is possible to maintain the inner venturi at any desired temperature and thereby effectively prevent the formation of ice on the venturi and the consequent choking of the air and fuel passages and condensation of the fuel.

In Figure 2 there is illustrated a construction similar to that shown in Figure 1 and parts corresponding in the two figures are designated by the same reference characters having a prime affixed thereto. In the construction of Figure 2 the inner venturi 5' is double or of compound nature, comprising an auxiliary venturi 12 serving to discharge the fuel and air into the secondary venturi 5'.

In Figure 3 there is disclosed a construction similar to that shown in Figure 1 with the exception that the inner venturi 13 is adapted to be heated by a liquid which may be supplied in any desired manner. For this purpose there is disclosed an inlet passage 14 and an outlet passage 15, insuring continuous circulation. The fuel or a mixture of fuel and air may be supplied laterally through a conduit 16 delivering into the venturi through the orifices 17.

The construction shown in Figure 4 is similar to that shown in Figure 3 with the exception that the inner venturi is of compound construction embodying a separate venturi 18 delivering to the secondary venturi 13'.

In the embodiment of the invention illustrated in Figure 5 the secondary venturi 19 may have a portion thereof surrounded with mica or other insulating material 20 upon which is wound suitable resistance material 21 adapted to receive a supply of electric current for maintaining the desired temperature conditions. Terminals 22 may lead outwardly from the coil 21 for attachment to any desired source of current. The entire coil may be enclosed within a protective covering 23. With this construction also fuel or fuel and air may be supplied through a conduit 24 to the orifices 25.

The embodiment of the invention illustrated in Figure 6 is similar to that shown in Figure 5, differing, however, as before described, in that the inner venturi 19' is of

compound construction, receiving a mixture of fuel and air from a still smaller venturi 26.

In other cases it has been found desirable to supply to the inner venturi air which has been preheated or which is at a definitely higher temperature than the air delivered to the main venturi. The advantages of such an operation may be obtained by a carburetor construction having the usual outer venturi 27 and an inner venturi 28 having its inlet connected to an air conduit 29 which in turn receives a supply of heated air from a stove or other heating means 30. The fuel for the inner venturi may be delivered through a laterally extending passage 31 discharging 80 through the orifices 32.

With all of the forms of the invention herein disclosed it is possible to raise the temperature of the inner venturi irrespective of the temperature of the outer venturi, and this constitutes an important advantage of the present invention.

I claim:

1. In a carburetor, a carbureting chamber having an expanding air inlet, an outer venturi receiving air from said inlet, an inner venturi receiving air from said inlet independently of the outer venturi and discharging into said outer venturi, and means intersecting the expanding air inlet for delivering a heating medium directly to the walls of said inner venturi, substantially as described. 90

2. In a carburetor, an outer venturi, an inner venturi positioned within the outer venturi and having a substantially unobstructed air flow space entirely around the same, such air space being established by a relatively limited supporting area between the venturis, and means in efficient heat conducting relationship to the inner venturi for directly heating the inner venturi irrespective of the temperature of the outer venturi and an air flow space. 100

3. In a carburetor, an outer venturi, an inner venturi positioned within the outer venturi and having a substantially unobstructed air flow space entirely around the same, such air space being established by a relatively limited supporting area between the venturis, and means in efficient heat conducting relationship to the inner venturi for directly heating the inner venturi at will and irrespective of its operating capacity. 110

4. In a carburetor, an outer venturi, an inner venturi having a limited area of, and relatively poor thermal, contact with the outer venturi, such contact being incapable of transmitting heat from the outer to the inner venturi with sufficient rapidity to prevent decrease in the temperature of the inner venturi when the carburetor is in operation, there being a substantially continuous annular passage between the outside of the inner and the inside of the outer venturi, and means extending entirely around 125 the inner venturi. 130

and in efficient heat conducting relationship to the inner venturi for raising the temperature of the inner venturi irrespective of the temperature of the outer venturi, substantially as described.

5. In a carburetor, an outer venturi, a compound inner venturi having an expanding ajutage extending into the outer venturi and terminating in substantially the region of
10 maximum depression therein, and heating means for raising the temperature of at least a portion of the inner venturi independently of the temperature of the outer venturi, substantially as described.

15. 6. In a carburetor, an outer venturi, an inner venturi having a limited area of, and relatively poor thermal, contact with the outer venturi, such contact being incapable of transmitting heat from the outer to the inner
20 venturi with sufficient rapidity to prevent decrease in the temperature of the inner venturi when the carburetor is in operation, there being a substantially continuous annular passage between the outside of the inner
25 and the inside of the outer venturi, and a second passage for raising the temperature of the inner venturi irrespective of the temperature of the outer venturi, said means comprising a heating chamber cooperating with
30 the inner venturi, substantially as described.

7. In a carburetor, an outer venturi, an inner venturi having a limited area of, and relatively poor thermal, contact with the outer venturi, such contact being incapable of
35 transmitting heat from the outer to the inner venturi with sufficient rapidity to prevent decrease in the temperature of the inner venturi when the carburetor is in operation, there being a substantially continuous annular passage between the outside of the inner
40 and the inside of the outer venturi, and means for raising the temperature of the inner venturi irrespective of the temperature of the outer venturi, said means comprising a heating chamber cooperating with the inner venturi and surrounding at least a portion of the inner venturi, substantially as described.

45 In testimony whereof I have hereunto set my hand.

50 ANTONIN BOULADE.
